GARMENT HANGING SCREEN

Harry Derman, Great Neck, N. Y.

Application January 17, 1947, Serial No. 722,643

4 Claims. (Cl. 160—127)

1

This invention relates to screens employing a plurality of sections hingedly coupled to adjusted the sections one with respect to the other in forming enclosures. Still more particularly, the invention deals with means for hanging garments or garment hangers from upper portions of the screen, said means being in the form of supporting hooks, so shaped, in conjunction with the contour of upper edges of the screen, as to frictionally support the hooks within boundaries of the screen when not in use and forming strong supporting hooks for garments or garment hangers when in extended position with respect to the screen.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of the upper portion only of a screen showing a number of the supporting hooks thereon in different positions; and

Fig. 2 is a detail view of the upper portion of one screen on an enlarged scale indicating the means for tensionally retaining a hook in inoperative position.

In screens of the kind under consideration, particularly when they are used as a means for forming an enclosure, behind which a party may disrobe, no means has been provided for support of garments removed from the body except on a chair arranged within the environment or by throwing the garments on top of the screen.

It is the purpose of my invention to provide on screens of the kind under consideration a simple, economical and practical form of garment or garment hanger supporting hook, whereby means is provided for supporting garments upon the inner surface of the screen in uses as indicated above.

In Fig. 1 of the drawing, I have shown at 5, 6 and 7 three screen sections, the sections 5 and 7 being end portions and hinged to the upright rails or frame members of adjacent sections, as indicated at 18. Each section has an upper finishing strip 9, 10 and 11, which strips are all of the same general contour and have the irregular or curved edges, as at 12, 13 and 14, these edges having, at their ends, common concaved surfaces, as indicated at 15, 15' on the strip 9; 16, 16' on the strip 10; and 17, 17' on the strip 11. Centrally of each of the recesses 15, 16 and 17 is an aperture extending downwardly through the strip

2

and one of these apertures is indicated at 18 in the strip 9 of Fig. 2 of the drawing. In said figure is also shown the recess 15, for illustrative purposes. At 19, in Fig. 2, is shown one of the supporting hooks or bracket members and, as these members are all of the same construction, like references identify like members in the respective showings. As indicated in Fig. 1 of the drawing, these members can be normally retained within the boundaries of the respective recesses so as to become substantially non-visible and to form no objection whatever or can be swung to extend at substantially right angles to one side surface of the screen sections. Three of the members are shown in extended position in Fig. 3 and three are shown in the collapsed position.

The members 19 include rod portions 20, note Fig. 2, which fit snugly in the apertures 18 and upper curved arm portions 21, the curvatures of which are normally as indicated in dot-dash lines at 21' in Fig. 2, so that, in assuming the collapsed position, the curved arms are tensioned slightly to frictionally engage the surface of the recess 15, thus retaining the members 19 against accidental displacement. It will be apparent, however, that the ends 21 may be forcibly moved into extended positions and, when in extended position, the curvatures form upwardly extending free end portions 22 which will retain the garment from displacement from the supporting hook or bracket, as well as to retain a garment hanger from displacement.

In the present construction, the curved ends 21 will substantially conform to the contour of the respective recesses 15, 16 and 17 etc. when in their collapsed position and, thus, will become substantially invisible upon the screen. Furthermore, these members are contained within the boundary of the strips 9, 10 and 11, thus facilitating packaging and shipment thereof.

In addition to supporting garments in the manner described, when screens are used for display or other purposes, the hooks may be utilized in support of articles of any type or kind on the screens; furthermore, my invention is not necessarily limited to any particular location of the supporting hooks and the heavy strips of the frames may be shaped to position the hooks thereon and also to control, to some degree, the resulting shape of the hooks employed.

In the construction shown, the separate screen sections comprise heavy bordering frames of which the strips 9, 10 and 11 form a part and the main body portion of the screen has relatively thin panels, as at 23, 24 and 25.

From the standpoint of description, the garment hanging device or hook may be said to comprise a mounting end portion adapted for arrangement in the socket of a support and a finger end portion extending angularly with respect thereto, the finger portion being curved and terminating in an upwardly extending free end.

Having fully described my invention, what I claim as new and desire to secure by Letters Patent is:

1. A screen of the character described, said screen comprising hingedly coupled sections, each section having, at its upper end, a rail terminating in an upper curved surface, said rail centrally of a curved surface having a vertical aperture, a hanger hook comprising a part fitting in the aperture of said rail, and a curved finger conforming generally to the contour of the curvature of said surface and frictionally engaging the surface to retain the hook against accidental displacement therefrom within the side boundaries of said rail.

2. A screen of the character described, said screen comprising hingedly coupled sections, each section having, at its upper end, a rail terminating in an upper curved surface, said rail centrally of a curved surface having a vertical aperture, a hanger hook comprising a part fitting in the aperture of said rail, a curved finger conforming generally to the contour of the curvature of said surface and frictionally engaging the surface to retain the hook against accidental displacement therefrom within the side boundaries of said rail, the finger of said hook being adapted to be extended angularly with respect to the rail in the use thereof, and the free end of the finger having an upturned end.

3. In screens having a number of hingedly coupled sections, each section having, at its upper end, a rail, the upper surface of the rail having, at end portions thereof, substantially semi-circular concaved surfaces, the rails centrally of the concaved surfaces having vertical apertures, garment hanger hooks movably supported in the apertures of said rail, and said hooks having curved finger portions conforming generally to the curvature of said curved surfaces and tensioned to engage the concaved surfaces in supporting the hooks against accidental displacement and within side boundaries of said rail.

4. The combination with a screen having a plurality of hingedly coupled sections, of means at the upper portions of the sections for hanging articles thereon, and said last named means comprising hook-type members adapted to be arranged angularly with respect to the sections and to be retained within boundaries of the sections when not in use.

HARRY DERMAN.
